Primary Examiner — George D. Kirschbaum*Assistant Examiner* — Natasha Vujcic*(74) Attorney, Agent, or Firm* — Manabu Kanesaka(57) **CLAIM**

The ornamental design for air-conditioner, as shown and described.

DESCRIPTION

FIG. 1 is a perspective view of an air-conditioner showing my new design;

FIG. 2 is a front view thereof;

FIG. 3 is a rear view thereof;

FIG. 4 is a plan view thereof;

FIG. 5 is a bottom view thereof;

FIG. 6 is a left side view thereof; and,

FIG. 7 is a right side view thereof.

The broken lines depict portions of the air-conditioner that form no part of claimed design.
